UNITED STATES PATENT OFFICE.

ROBERT BROOKS, OF PATERSON, NEW JERSEY.

DESIGN FOR HANDKERCHIEF AND SHAWL.

SPECIFICATION forming part of Design No. 12,145, dated February 1, 1881.

Application filed December 20, 1880. Term of patent 3½ years.

To all whom it may concern:

Be it known that I, ROBERT BROOKS, of the city of Paterson, county of Passaic and State of New Jersey, have invented a new and useful Design for Handkerchiefs and Shawls, of which the following is a specification, reference being had to the accompanying drawing, forming a part thereof, in which the figure is a plan view of my newly-invented design.

Heretofore designs for handkerchiefs and shawls have presented to the view a border composed of the same figure extending all the way around the handkerchief or shawl, while the leading feature of my newly invented design consists in a dividing line, A, drawn diagonally, which divides the design into two equal parts, B C, the borders of which are composed of different figures.

Part B has a border composed of straight bars, *a b*. *a* is entirely plain, and *b* has oblique lines running across the bar. The bars *a b* commence at the diagonal line A and die away or terminate at the block or square *d*, which block or square *d* is composed of small squares or checkers formed by diagonal lines *e e'*.

Part C has a border composed of fan and leaf work. In the angle or corner *f* there is a half-fan-shaped figure, *o*, above a straight bar, *g*. Against the bar *g* there is a curved bar, *h*, the ends of which terminate at leaf-work *i*. Within the space formed by the curved bar *h* there is a butterfly, *j*, with expanded wings, and fan-work, and in front of the butterfly is a circular figure, formed by the indented bar or border *k*, the ends of which terminate at bars *l*, which form the outlines in part C of the center to the general design. Within the in-

dented circular bar or border *k* there is fan-work composed of four blades, and leaf-work of three and four leaves. In the angle formed by bars *l* and line A there are quarter-circles *m*, the ends of which all terminate at bars *l* and diagonal line A, and within these quarter or parts of circles are three fan-blades, with small pointed ornaments between them. Between the leaf-work *i* and *p* there are corbels *s*, and below the corbels there is leaf-work *t*, supporting the corbels *s*. At either end of the same there is leaf-work *p*, within the curve of which there is fan-work *n*. Between the leaf-work *i* and *p*, and between *p* and the angles formed at top and bottom of figure C and the diagonal line A, there are boughs containing leaves *r* with half-corbels and half-leaves appearing as cut off by the diagonal line A. The center *q* is composed of sprigs having leaves thereon.

The colors for my new design are not considered as an essential feature thereof; but any suitable colors may be used.

What I claim, and desire to secure by Letters Patent, is—

1. The design for handkerchiefs and shawls, consisting of parts B and C, formed by diagonal line A, as shown and set forth.
2. The part B, consisting of bars *a b*, block or square *d*, as shown and set forth.
3. The part C, consisting of figures *o g h i j k l m n r s t p q*, all arranged as shown and set forth.

ROBERT BROOKS.
